(74) Attorney, Agent, or Firm — Ostrolenk Faber LLP

(57) **CLAIM**

The ornamental design for an active substance container for diffusers, as shown and described.

DESCRIPTION

(30) **Foreign Application Priority Data**

Nov. 10, 2016 (ES) 0524412

(51) LOC (11) Cl. 28-99

(52) U.S. Cl. USPC D23/366

(58) **Field of Classification Search**

USPC D23/207, 208, 360, 364-369, 388; D22/119, 122

CPC A61L 9/00; A61L 9/02; A61L 9/03; A61L 9/034; A61L 9/04; A61L 9/12; A61L 9/032; A61L 9/122; A61L 9/127; A61L

1. Active substance container for diffusers
- 1.1 is a bottom plan view.
- 1.2 is a front elevation view.
- 1.3 is a rear elevation view.
- 1.4 is a right side elevation view.
- 1.5 is a top plan view.
- 1.6 is a top, front perspective view.
